(Model.)

W. H. NAUMAN.

Grain Drill.

No. 233,109.

Patented Oct. 12, 1880.

UNITED STATES PATENT OFFICE.

WILLIAM H. NAUMAN, OF DAYTON, OHIO.

GRAIN-DRILL.

SPECIFICATION forming part of Letters Patent No. 233,109, dated October 12, 1880.

Application filed March 13, 1880. (Model.)

To all whom it may concern:

Be it known that I, WM. H. NAUMAN, of Dayton, in the county of Montgomery and State of Ohio, have invented certain new and 5 useful Improvements in Grain-Drills; and I do hereby declare the following to be a full, clear, and exact description of the same.

My invention relates to an improvement in grain-drills; and my improvements consist, 10 first, in a new force-feed mechanism; secondly, in an improved reversible scattering-board; and, thirdly, in a novel conveyer-tube hanger.

The novelty of my force-feed mechanism, which belongs to that class in which the feed- 15 wheels on a common shaft are shifted laterally to regulate the feed, consists in providing the feeding cylinder or wheel with ribs or blades, which, by sliding said cylinder, are made deeper or shallower without shortening 20 their length, so as to expose more or less of their forcing-surface to the grain, and thereby regulate the amount fed.

The novelty of my remaining improvements 25 consists in their constructions and combinations, all as will be herewith specifically set forth.

In the accompanying drawings, Figure 1 is 30 a sectional view, in side elevation, of so much of a grain-drill as exhibits the relative positions of my improvements. Fig. 2 is an enlarged perspective view of one end of my reversible scattering-board. Fig. 3 is a side elevation of my improved feed-wheel cylinder. Figs. 4 and 5 are side and end elevations of 35 my skeleton-cylinder and washers. Figs. 6 and 7 are plan and side elevation of the cup or wheel casings. Fig. 8 is a perspective view of the cup-saddle. Fig. 9 is a near elevation of the cup and contained feed devices. Figs. 10 and 11 are plan and side elevation, in section, 40 of my improved conveyer-hanger. Fig. 12 is a side elevation of a modification in the construction of the feed-wheel.

The frame-work and general organization of 45 the machine may be of the usual or any suitable construction, A representing the seed box or hopper; B, the grass-seed hopper; b, the side beams, and D E the cross-beams; F, the drag-bars; G, the hoes, and H the conveyer- 50 tubes.

The cups in which the feed-wheels rotate,

Figs. 6, 7, 8, and 9, consist of the lower or receiving portion, I, with a rounding bottom having laterally-projecting pins a, upon which the conveyer-tubes are hung. These cups, 55 which are secured upon the bottom of the hopper in the usual way, are open upon each side, and have the discharge-orifice b for the grain upon the rear or ascending sides of the feed-wheels. In each cup is placed a skeleton-wheel, J, Figs. 4 and 5, which is just as wide as the cup, and which is composed of two annular washers, c d, united by equidistant ribs e. These washers are of equal external diameter, and snugly fit into the side aperture of 60 the cup I. The bore of the washer c is somewhat smaller than that of the washer d, and the ribs e, which are set radially, are flush on their under surfaces with the bore of the washer c, while they project within the bore 65 of the washer d, as seen in Fig. 5. To hold this skeleton in place I employ the saddle K, Figs. 7 and 8, which, being provided with shoulders f and g, when let into the top of the cup I, is self-locked therein against lateral displacement, and also, by reason of the shoulders g, which bear against the inner edges of 70 each of the washers, prevents the skeleton-wheel from slipping laterally, though it is free 75 to revolve.

The feed-wheel shaft L, receiving its rotation in the usual or any suitable way, runs centrally through the bores of the washers and has keyed upon it the wheel-cylinders M, Figs. 3 and 9. These cylinders are twice as long as 80 the width of the cups, and have one half of 85 their length smooth to slide snugly through the bore of the washer c and against the under sides of the ribs e. The other half of the cylinder has raised ribs h upon it, which enter the larger bore of the washer d and fit snugly between the ribs e, as seen in Fig. 9.

The tops of the ribs e project above the tops of the ribs h, so that the former can always feed even when the ends of the ribs h are in 95 contact with the washer c. By this means I produce a feed-wheel which will always feed the grain through to a very limited and the slightest extent when the ribbed portion of the cylinder is entirely within the cup. As 100 this ribbed portion is drawn out the ribs e are gradually exposed, thus enlarging the feed-

cells and gradually increasing the discharge of the grain. Any suitable means may be employed in connection with a gage-plate for sliding the feed-shaft to sow any required quantity of grain.

As a modification of the above construction the feed-wheel may be constructed as in Fig. 12, where it is ribbed its entire length, but where the depressions between the ribs for half its length are deeper than between the ribs for the other half. With such a wheel the washers would be unconnected by ribs, as in Fig. 4, but each would have apertures to form its bore corresponding to the shape of each respective half of the feed-wheel. By this lateral construction the same effect in feeding would result as in the former construction—that is, the wheel would feed at all times through to the least possible extent when the enlarged portion was wholly within the cup. The object of this improvement is to prevent crushing of the grain, which is such a source of difficulty and a serious objection to most force-feeds.

With the above mode of operation there are no stationary side portions of the cup or followers against which the grain can be caught and crushed.

My improved reversible scattering-board for depositing the grass-seed either in front or behind the drilling or cultivating hoes consists of a board, R, of suitable width and thickness, having projecting metal straps *i* secured upon each end, as seen in Fig. 2, to form metal-bound slots in the ends of the board.

Upon the inner sides of the side beams, C, directly under the grass-seed box, are fastened metal plates O, Fig. 1, carrying at the upper central portion a pin, j, to fit into the slot k of the scattering-board. Upon the lower outer corners of the plates O are lugs l, having stop-shoulders m, and above these are guide-pins n, as seen in Fig. 1.

To apply the scattering-board it is only necessary to slip its slots over the pins j , which serve as pivots, and, by sliding the board down obliquely until the lower open ends of the slots pass over the lugs l , it becomes set, as seen in Fig. 1. In this position the grass-seed is deposited in the rear of the hoes.

To shift the board it is only necessary to slide it up and swing it upon the pins *j*, when it can be lowered and locked, as before, in the position shown by the dotted lines, Fig. 1, in which position the seed is thrown front of the hoes. This forms a simple attachment, which enables the scattering-board to be reversed without removing or detaching it from the frame.

- It can be readily understood that instead of slotting the ends of the scattering-boards

slots may be made in the side plates, O, and the pivot may be situated upon the ends of the scattering-board.

My conveyer-hanger, Figs. 10 and 11, to which the tubes II are attached, consists of a metal tube, a' , with a flaring rear upper portion extending laterally to form hooks b' , adapted to slip over the pins a of the cups, and thereby suspend the tubes. 70

In many machines the jumping off or detachment of these tubes during the operation of the drill, caused by going over uneven ground, is a fruitful source of trouble. To remedy this and form a detachable lock is the object of this improvement; and to this end I pivot a gravitating latch, c' , in the front portion of the tube a' , as shown particularly in Fig. 11. This latch, of the shape indicated, when depressed at its lower portion is thrown into the position indicated by the dotted lines. In this portion the hooks b' can be slipped over the pins a to secure the conveyer-tubes to the cups. Now, upon letting go of the latch it falls, by gravity, back to the first position, and bears against the rounded bottom of the cup, thus forming a toggle-joint, which prevents the tubes from being removed unless the latch is depressed.

Having thus fully described my invention, go to claim.

1 claim—
1. In the force-feed mechanism of grain-drills, the combination, with each cup, of a laterally-adjustable feed-wheel having two sets of blades or ribs forming feed-cells of varying depths and widths, for the purpose specified.

2. In the force-feed mechanism of grain-drills, the combination, with annular washers, of laterally-adjustable feed-wheels having for each cup two sets of blades or ribs forming feed-cells of varying depths and widths, for the purpose specified.

3. In the force-feed mechanism of grain-drills, the feed-wheel consisting of a skeleton-wheel composed of washers and connecting-ribs and a contained laterally-sliding ribbed cylinder, as and for the purpose specified. 105

4. The reversible sliding and swinging scattering-board having slots in its ends, in combination with pivot-pins and adjusting-stops, as and for the purpose specified. 110

5. The combination, with a conveyer-hanger, of a gravitating latch for preventing the accidental disengagement of the tubes, as set forth.

In testimony whereof I have hereunto set my hand.

WM. H. NAUMAN.
